UNITED STATES PATENT OFFICE

122,155

DESIGN FOR A COMBINED CULINARY BEATER AND MIXER, OR SIMILAR ARTICLE

Rudolph Bernhardt, Chicago, Ill.

Application February 16, 1940, Serial No. 90,314

Term of patent 3½ years

To all whom it may concern:

Be it known that I, Rudolph Bernhardt, a citizen of the United States and resident of Chicago, in the county of Cook and State of Illinois, have invented a new, original, and ornamental Design for a Combined Culinary Beater and Mixer, or Similar Article, of which the following is a specification, reference being had to the accompanying drawing, forming a part thereof.

In the drawing:

nary beater and mixer, or similar article, showing my new design;

Figure 2 is a side elevational view; and

I claim:

The ornamental design for a combined culinary beater and mixer, or similar article, as shown.

RUDOLPH BERNHARDT.
